(57) **CLAIM**

The ornamental design for a seat rail for motorcycle, as shown and described.

DESCRIPTION

FIG. 1 is a front view of a seat rail for motorcycle showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a right front perspective view thereof;

FIG. 8 is a left front perspective view thereof;

FIG. 9 is right rear perspective view thereof;

FIG. 10 is a left rear perspective view thereof; and,

FIG. 11 is a rear perspective view illustrating the position of use on a motorcycle.

The broken lines shown in FIGS. 1-11 are for the purpose of showing environmental structure only and form no part of the claimed design.
